ANTENNA HOUSING

Daniel M. Adams, Birmingham, Mich., assignor to General Motors Corporation, Detroit, Mich., a corporation of Delaware

Application December 29, 1955, Serial No. 39,521

Term of patent 7 years.

(Cl. D14—6)

Figure 1 is a front elevational view of an antenna housing according to my new design;

Figure 2 is a top plan view of the antenna housing;
Figure 3 is a side elevational view of the antenna housing of Figure 1;

Figure 4 is a sectional view taken on the plane indicated by line 4—4 of Figure 1; and

Figure 5 is a rear elevational view of the antenna housing.

The fragmentary portions of the antenna shown by means of broken lines are disclosed for illustrative purposes only.

I claim:

The ornamental design for an antenna housing, substantially as shown and described.
